UNITED STATES PATENT OFFICE.

FRANCIS LECLÈRE, OF PHILADELPHIA, PENNSYLVANIA.

SPINDLE-STEP RAIL FOR SPINNING-FRAMES.

SPECIFICATION forming part of Letters Patent No. 255,518, dated March 28, 1882.

Application filed December 21, 1881. (No model.)

To all whom it may concern:

Be it known that I, FRANCIS LECLÈRE, a citizen of the United States, residing at Philadelphia, in the county of Philadelphia and 5 State of Pennsylvania, have invented a new and useful Improvement in Spindle-Step Rails for Spinning-Frames, of which the following is a specification.

My invention consists in providing the spindle-step rail of spinning-frames with clasping-bearings which are in part rigid with the rail and in part yielding independently of the same, said bearings being of metal homogeneous with that of the rail, and serving, when the 10 spindle-steps are set in position upon the rail and the pressure of set-screws or wedges is brought to bear against the yielding portions of the bearings, to produce a frictional bind upon the periphery of the spindle-steps, so that 15 said steps are firmly held from incidentally slipping up or down while the machine is in operation.

My mode of construction is very simple and cheap, while it affords a more effective and 20 convenient means for adjusting and firmly and securely holding cylindrical spindle-steps in position upon the step-rail of spinning-frames.

In the accompanying drawings, Figure 1 is a front perspective view of a portion of the 25 step-rail of a spinning-frame to which my invention of clasping bearings for spindle-steps is applied. In this view two spindle-steps and two adjusting-screws are shown, and also the transverse form or profile of the rail, as well 30 as the top and front side. Fig. 2 is a back view, in elevation, of the portion of spindle-step rail shown in Fig. 1, showing the spindle-steps, clasping-bearings, and adjusting-screws, the latter being represented by dotted circles. Fig. 35 is a horizontal section of the rail, clasping-bearings, and spindle-steps in the line $y-y$ of Fig. 2, the rail and other parts being inverted, and that of the rail which constitutes its top, and also the adjusting-screws, being shown in 40 inverted plan view. Fig. 4 is a vertical transverse section of the rail with its clasping-bearing clasping a spindle-step which is shown partly in elevation, and in section by breaking out a portion thereof at the upper end.

50 A in the accompanying drawings is a step-rail of a spinning-frame. In transverse section

it may be of usual form on its upper and front faces. This rail is made of cast metal, either steel or iron, and if of iron the metal may be rendered malleable by the ordinary mode. 55

On the under side of the cap portion a of the rail a clasping-bearing, B, of homogeneous metal with that of the rail, is formed. This bearing is of a form as shown in Fig. 3, which enables it to almost completely encircle a spindle-step, C, and from the said spindle-step it extends longitudinally parallel, or nearly so, with the front portion, b , of the rail a considerable distance, as shown at e in Fig. 3. All that part of the bearing B which is made to touch 60 and inclose the spindle-step C and to extend longitudinally from it is constructed in relief from the cap portion a of the rail A; and said bearing is rigidly connected to the rail, as at c , being cast upon the under side of the said 65 cap portion, as indicated in Figs. 2, 3, and 4 of the drawings.

On the rear side of the portion b of the rail projecting bosses f are cast, and between these bosses are recesses d of segmental form. The 70 bosses and recesses are of a depth about equal to the bearing proper, B. The recesses d allow the bearings proper, B, beyond their connecting portion, c , to expand and move away from the spindle-step when the same are relieved of 75 pressure. In rear of each of the bosses f the leverage end e of a bearing proper, B, is extended horizontally, so as to be in relief from the rail beyond the point of connection c , and also to stand in rear of an adjusting-screw, D, 80 or other analogous adjusting device, as shown in Fig. 3. Through the bosses and portion a of the rail screw-threaded holes are formed, and into the same tightening or set screws D are passed and made to bear against the front 85 surfaces of the leverage ends e of the bearings. By means of the screws D the yielding portions of the bearings can be made to bind firmly around the periphery of the spindle-steps, and thereby hold the steps from moving 90 up or down. The nicked ends of the screws are on the front side of the rail A, and thus is afforded great convenience for tightening up the bearings around the spindles from the front of the frame. 95

Instead of using screws for setting up the bearings, wedges might be driven up verti-

cally between the bosses *f* and the leverage ends *e* of the bearings; but I much prefer the screws, as the adjustments can be made quicker and from the front of the rail, whereas with 5 the wedges the adjustment would require to be made from the rear thereof.

I have found that cast-metal bearings *B* having simply a rigid connection at *c* with the rail will yield sufficiently, without danger of 10 fracturing the metal, for effecting the firmest desirable hold upon the spindle-steps; and this being so, the rail and bearings can be cast together of homogeneous metal at a cost much less than that at which rails and ordinary 15 bearings can be produced. Besides this, my construction of bearings is found even more effective for holding the steps in place, and more convenient for adjustment of the spin-

20 dle-steps with respect to the spindles, as occasion requires.

My invention might be employed in connection with other than spindle-step bearings to advantage.

What I claim as my invention, and desire to secure by Letters Patent, is—

25 A spindle-step rail, *A*, provided with a clasp-
ing-bearing, *B*, which is cast with the rail,
said bearing having a rigid connection with
the rail, as at *c*, and being free from said rail
at all other points, substantially as and for the 30
purpose described.

FRANCIS LECLÈRE.
